UNITED STATES PATENT OFFICE.

PAUL S. GILL, OF CLEVELAND, OHIO.

DESIGN FOR A FLAG, PENNANT, SIGN, EMBLEM, OR AN ARTICLE OF A SIMILAR NATURE.

54,737.

Specification for Design.

Patented Mar. 23, 1920.

Application filed December 16, 1918. Serial No. 267,058. Term of patent 7 years.

To all whom it may concern:

Be it known that I, PAUL S. GILL, a citizen of the United States, residing in Cleveland, in the county of Cuyahoga and State of Ohio, have invented a new, original, and ornamental Design for Flags, Pennants, Signs, Emblems, or Articles of a Similar Nature, of which the following is a specification, reference being had to the accompanying drawing, forming part thereof.

The figure is an elevation of a flag, showing my new design.

The flag consists of an upper horizontal

red band and lower horizontal blue band, an intermediate horizontal white band, and two vertical khaki-colored bands superposed upon said aforementioned red, white and blue bands.

I claim:

The ornamental design for a flag, pennant, sign, emblem, or an article of a similar nature, as shown.

Signed by me, this 26th day of November, 1918.

PAUL S. GILL.
